HINGE SYSTEM FOR REFRIGERATED CABINETS

Filed June 12, 1948

UNITED STATES PATENT OFFICE

2,607,411

HINGE SYSTEM FOR REFRIGERATED CABINETS

Paul D. Van Vliet, Chicago, Ill., assignor to Liquid Carbonic Corporation, Chicago, Ill., a corporation of Delaware

Application June 12, 1948, Serial No. 32,627

1 Claim. (Cl. 160—231)

1 This invention relates to an improvement in the hinging of two lids or covers which may be used to close a horizontal opening in a cabinet.

One purpose is to provide a continuous closure for the full length of the hinge, to prevent drip through the hinge to the goods stored below.

Another purpose is to provide an easily separable hinge system to facilitate cleaning.

Another purpose is to provide an easily replaceable and cheap hinge member, with a low maintenance cost.

Another purpose is to provide a hinge and means for attaching it to lids or covers, without requiring tools for installation.

Another purpose is to provide a hinge and means for attaching it to lids or covers, which has no cracks or crevices which are not accessible for cleaning by a brush, and without the use of tools.

Other purposes will appear from time to time in the course of the specification and claim.

I illustrate my invention more or less diagrammatically in the accompanying drawings wherein:

Figure 1 is a vertical section through two lids connected by a hinge structure embodying one application of my invention.

Figure 2 is a partial plan view illustrating the hinge structure;

Figure 3 is a transverse section on a somewhat enlarged scale, illustrating a hinge retainer;

Figure 4 is a side elevation of the structure shown in Figure 3;

Figure 5 is a transverse section through the flexible hinge member itself;

Figure 6 is a partial vertical section, similar to Figure 1, but illustrating a variant form of the invention;

Figure 7 is a section similar to Figure 6, illustrating another form of the invention; and

Figure 8 is a vertical transverse section on an enlarged scale, illustrating one of the hinge retainers shown in Figure 7.

Like parts are indicated by like symbols throughout the specification and drawings.

Referring to the drawings, I generally indicate the cabinet wall. 2 generally indicates two lids or covers for closing any suitable opening surrounded by the cabinet wall 1. The lids may be of any suitable material, but in Figures 1 and following I illustrate them as formed of an upper metal wall 3 and a lower metal wall 4, the two walls being connected by a side wall 5. The space between may be filled by any suitable insulation, such as a cork fill 6. The edges of the lids which engage the upper end of the cabinet wall 1 may be suitably formed as at 7 to provide an overlying flange.

My invention relates primarily to the hinging together of the two lids. In Figure 5 I illustrate a hinge 20 of rubber or a suitable rubber substitute, such as a flexible plastic which is formed

5 with a relatively thin web 21 in which flexing occurs when the hinge is used. The hinge member terminates in enlargements or bulbous edge portions 22 which are preferably of the general shape of the references in the below described hinge retainers, into which the bulbous edge portions may be threaded lengthwise. I employ a layer of fabric 21a to limit the stretch of the hinge member without reducing its flexibility.

10 The hinge retainers on the doors are, in Figures 1 to 4, illustrated as metal channels 10, which may be welded or otherwise secured to the top lid walls 3, as at 11, and which have longitudinal openings 12 of sufficient width to permit the extension therethrough of the web portion 21 of the hinge. The bulbous portions 22 are confined within the retainers, and thus provide lateral retention of the hinge. It will be understood that the retainers 10 are preferably open at each end. 15 Thus the hinge element 20 may be longitudinally slipped into the retainers, and also readily removed. When the hinge 20 is removed, then the interior of the retainers is readily accessible for cleaning. The hinge 20 also serves as a roof or closure over the space or joint between the two lids 2, preventing any leakage or spillage or dripping into the interior. As a matter of convenience, as shown in Figure 2, the hinge member 20 may be slightly longer than the retainers 10. 20 However, it is of substantially the same width as the aperture closed by the lids.

25 Whereas, in Figures 1 and 3, I have illustrated the retainers 10 as roughly rectangular, it will be understood that they may be formed in any suitable shape, so long as an enlarged hinge edge portion may be slipped endwise into them. It may be convenient, and advantageous, to have the bulbous edge enlargement 22 conform generally to the inner faces of the retainer 10, but this 30 is not strictly necessary, and I do not wish to be so limited.

35 Referring to Figure 6, I illustrate a variant form of my invention in which two lids 30 may be formed of a suitable plastic, their upper walls 31 having molded therein retainers in which integral portions 32, 33 define a longitudinal channel 34, which is open at the ends, and has a restricted longitudinal opening 35 through which the web 21 of the flexible hinge member may pass. 40 The bulbous enlargement 22 is received in the channel, as shown in Figure 6. The operation of the hinge is precisely the same as in the structure of Figure 1, but this application is practical, where molded or preformed lids are used.

45 Figures 7 and 8 illustrate a further modification in which hinge retainer inserts, generally indicated as 41, may be molded into plastic lids 40.

50 In the forms of Figures 6 and 7, the hinge retainer recesses are generally C-shape. In the

form of Figures 1 to 4, where a sheet metal retainer is used, the form may also be described as roughly C-shape, all forms having in common that an open-ended channel, with a longitudinally extending, but restricted, side opening, is provided. In Figure 7, however, the retainer 41 is partially embedded in the molded lids 40. The relatively thin walls 42 and 43 define an opening 44 of the proper contour to receive and retain the bulbous edge 22 of the hinge member 20. A thin flange 45 extends downward from the head portion thus formed, and serves to anchor the retainer into the lid body 40. It may have perforations 46 to permit the material on both sides to bond through the holes for strength. A key 47 may be formed in the lower face of the head to anchor the head securely into the lid body.

It will be noted that all of the three forms are identical in that they use a flexible hinge continuous from lid to lid, without a break across the width of the cabinet opening, and in that they all provide means to retain the bulbous edges of the hinge to the lids. The hinge may be separated from each lid by withdrawing the hinge edges lengthwise of the recess.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of the invention are as follows:

The current hinging systems used in refrigerated cabinets do not meet all requirements. The New York Board of Health, for example, has promulgated rulings which call for a change in the current system of hinging, because present hinges require a separate fastening of the hinge to the lid body, where metal hinges are used, or require the use of separate hinge retainer strips, where a rubber hinge is used. These fastenings provide cracks or spaces for the accumulation of ice cream solids which, in time, become rancid, bacteria laden, or both, which causes a condition unsanitary for food storage. A metal hinge is approved if the hinge leaves are integral with the metal of the lid, providing that the hinge pin is removable, and large enough to permit running a brush through the curl of the hinge. This makes it practically impossible, in areas where the New York Board of Health rule, or an equivalent rule, applies, to use a metal hinge which is of good appearance or is practicable in use.

The New York Board of Health also rules that the hinge system must be so constructed that water or spilled liquids lying on the top of the lid may not drop through the hinge when the lid is lifted 90°, or is flipped over 180°. The usual metal hinge does not meet this requirement, but the continuous rubber hinge does form a tight roof over the gap between lids, providing it is suitably and continuously anchored to each lid.

The present invention provides a rubber hinge which, when applied to a common type of refrigerated cabinet, may be some 11 inches long by about $\frac{3}{4}$ inch wide. It may be approximately $\frac{1}{8}$ inch thick, through a central width of perhaps $\frac{3}{8}$ inch, this being the portion indicated at 20 in Figure 5. Its edges are enlarged, as at 22, for lengthwise insertion in the recess of the hinge retainer 10. All forms of the invention operate

substantially alike. Taking the form of Figures 7 and 8 as an example, the retaining or holding members 41 may be of extruded aluminum or other suitable material, and may be molded integrally with the plastic lid body 40. The material of the lid bridges through apertures 46, and this, with the key 47, provided a unitary structure in which there is no space or crack permitting the access of substances which will decay or become rancid. The exposed part of the members 41 may, in transverse section, be roughly shaped like the letter C, with a small opening 44a and a large recess 44 behind the opening. This recess is formed to receive the portion 22 of the hinge, which may be inserted lengthwise of the member 41. This hinge has the advantage that the lids or covers 40 may be separated readily, without tools, for easy cleaning of the hinge structure itself, and also for cleaning of the recesses 44. This structure meets the requirements of cleanliness, performs substantially as the conventional hinge, and is not unduly expensive. It permits an easy replacement of a torn hinge, and has the advantage of older rubber hinges, in that no water on the top of the lid can pass down through the gap between adjacent lids to contaminate food below.

Whereas an extruded metal member, molded into the lid, has been suggested, it will be understood that any suitable material may be used, and in any suitable form. In Figure 6 is illustrated a variant form, in which, in place of a separate metal hinge retainer, a recess in the plastic material of the lid itself is shown. The upper wall 31 of the lid 30 is formed with a recess 34 of suitable shape to receive the enlargement 22 of the hinge strip. When this form is used no separate hinge retainer is necessary.

However, as a matter of general practice, I prefer the form of Figures 1 to 4, in which an all-metal lid is used, with retainer channels 10 welded or otherwise secured to the top lid walls 3. The retainer provides the necessary form of aperture or channel, and will take a flexible hinge 20 identical with the hinge elements used with the other forms.

I claim:

A hinge structure providing a readily removable hinge connecting a pair of closure lids for an access opening in the top of a refrigerated food cabinet and wherein the lids require frequent separation for cleaning, comprising a pair of horizontally-aligned lids supported when in closure position in side-by-side relation and having adjacent parallel side edges in substantially abutting relation, an elongated hollow hinge holder extending across each of the top surfaces of said lids along the adjacent side edges thereof, said hinge holders providing substantially enclosed recesses extending in generally parallel alignment with each other and having restricted lengthwise slots in the upper inner edges thereof and spaced above the lids providing access to said recesses, both said recesses and said slots being open at the same ends to permit the insertion and withdrawal of a hinge member, and an elongated flexible hinge member composed of a material having the characteristics of rubber and providing a central flexing portion extending between said hinge holders and having its edge portions extending through said slots and into said recesses, said edge portions being enlarged and substantially filling said recesses to prevent said edges from being pulled through said slots, the central flexing portion of said hinge member being bowed outwardly and thereby spaced from

the top surfaces of said lids to facilitate the insertion and removal of said hinge member by grasping an end of the central flexing portion, the enlarged edge portions of said hinge member being freely slideable within said recesses when the 5 lids are in closed position and said hinge is in its unflexed condition and frictionally engaging the walls of said recesses when said lids are opened, whereby said hinge member can be easily removed through the open ends of said slots and 10 recesses for the purpose of separating said lids to facilitate cleaning thereof, while said lids are prevented from shifting laterally with respect to each other when opened by the frictional engagement of the enlarged end portions with the walls 15 of the recesses.
